UNITED STATES PATENT OFFICE.

IRVING COWLES, OF CHICAGO, ILLINOIS.

VAPOR-FEED MEANS.

Application filed April 7, 1922. Serial No. 550,260.

To all whom it may concern:

Be it known that I, IRVING COWLES, a citizen of the United States, and resident of Chicago, in the county of Cook and State 5 of Illinois, have invented certain new and useful Improvements in Vapor-Feed Means, of which the following is a specification.

My invention relates to improvements in means for feeding vapors and gases to the 10 intake of an internal combustion engine.

The object of my invention is to provide means of a simple character and without moving parts through which air or other gases can be drawn into the intake of an 15 engine for adding air or other gases or vapors to the combustion gases flowing from the carburetor to the engine.

I arrange the device preferably in contact with the exhaust manifold in such a 20 manner that it becomes highly heated and when it is used to supply vaporized fluids such as water or hydrocarbon liquids to the engine intake, all material in liquid form supplied to the device is retained therein 25 until the liquid is vaporized and it cannot escape from the device and pass to the engine until it is in vaporized form.

A particularly advantageous feature of 30 my device is in the addition of water vapor to the combustion gases tending to prevent the forming of carbon in the cylinders. In such use the water may be carried into the device with air or be fed in without air but in either case the water is trapped in the 35 device and held there until it is vaporized before it can pass from the device to the engine intake.

A special feature of value relates to means arranged within the device for heating the 40 vapors after the liquid has been vaporized and has presumably produced a saturated vapor, the vapor is then heated to a higher temperature and thereby the condensation of the vapor after it enters the intake or 45 the cylinder is prevented.

The uses of my device are many but they all relate to the prevention of any fluids escaping from the device in liquid form.

In the feeding of water to the intake, if 50 the water feed starts with the starting of the engine, the water will be retained in the device until it becomes heated and vaporized by heat derived from the exhaust and this is in accordance with the needs as it is well 55 known that after the engine has become

heated and is running at normal speed that the addition of the water to the air is particularly advantageous.

My invention will be more readily understood by reference to the accompanying 60 drawing forming part of this specification and in which:

Figure 1 is a fragmentary side elevation of an internal combustion engine showing the exhaust and intake manifolds;

Figure 2 is a side elevation of a combined trap and vaporizer made in accordance with 65 my invention;

Figure 3 is a vertical sectional view of the vaporizer showing a side elevation of 70 the main body part with the cover removed and taken on the line 3—3 of Figure 4, parts being broken away to show the connecting pipes; and

Figure 4 is a vertical central section on 75 the line 4—4 of Figure 2, illustrating the device as mounted upon an exhaust manifold.

In said drawings, 1 represents the cylinder portion of an internal combustion engine having an intake manifold 2 and an exhaust manifold 3 of usual character. The intake manifold has an intake connection 4 adapted to be connected to a carburetor, not shown.

Upon the exhaust manifold 3, I secure one of my novel combined vaporizer and trap 5, the trap being provided with an externally threaded stem 6 adapted to be screwed into a threaded opening 7 in the 90 wall 8 of the manifold 3 and by means of which heat is readily and effectively transmitted to the body of the device from the exhaust manifold. The device comprises a circular box-like body portion 9 from the 95 rear wall 10 of which the stem 6 projects centrally. The body is open at its front, which open side is adapted to be closed by a flat cover 11, the cover being secured to the body by a number of screws 12. The back wall 10 and the cover 11 are parallel and the device has the form of a circular box.

At the lower side of the box, I provide an outlet pipe 13 the wall of the box being provided with a suitable thickened part 14 for connecting the pipe to the box. At one side of the box and just above the middle thereof, I provide a suitable internally threaded nozzle 15 for receiving an inlet pipe 16. Both the inlet and the outlet pipes 110

are of relatively small cross-sectional area. Between the inlet and the outlet pipe, I provide the body with a number of horizontal walls 17, 18, 19 and 20. These walls are integrally formed with the circumferential wall 21 of the body at alternate ends of same and with the back wall 10 and they all extend horizontally in parallel relation with each other. The alternate walls are connected at one end with the peripheral wall of the box at one side thereof and the intermediate walls are connected with the peripheral wall of the box at the other side thereof. For instance, the upper horizontal wall 20 is connected with the peripheral wall of the body at the right hand side and just below the inlet. The next lower wall 19 is connected at one end with the peripheral wall of the body at its left hand end. The next wall 18 projects from the right hand side of the body. This arrangement of these horizontal walls provides a zigzag passage 23 extending downwardly through the body between the several horizontal walls. The ends of the walls opposite to the ends where they are connected with the peripheral wall of the body are separated from the peripheral wall so that this passage 23 is continuous and is relatively quite long. The cross-sectional area of the passage 23 is several times the cross-sectional area of the inlet and outlet pipes so that as the vapors or gases are drawn through this passage, they flow at considerably less speed than they do through the outlet pipe and have ample opportunity to become highly heated by flowing in contact with the several heated walls. Projecting upwardly from the upper side of the upper horizontal wall 20, I arrange a series of vertically extending partitions 24, 25, 26 and 27. The outer partitions or baffles 24 and 27 are shorter than the middle partitions 25 or 26. Between the four vertically extending walls I provide pockets 28, 29 and 30 and I arrange depending walls 31, 32 and 33 which project down into these pockets, the lower ends of these walls extending below the upper ends of the shorter upwardly projecting walls 24 and 27 and provide a zigzag passage 34 between the inlet and the free end of the horizontal wall 20 through which all fluid, which enters the device from the inlet, must pass on its way to the outlet. The pockets 28, 29 and 30 in conjunction with the depending baffles form traps for catching and retaining any fluid in liquid form which may enter the device. These several traps, as described, are arranged in series, that is the entering liquid will first be trapped in the pocket 28 and if any liquid is carried over the wall 25 it will be trapped in the pocket 29 and if any liquid is carried from this pocket over the vertically extending wall 26, it will be trapped in the last pocket 30.

The several walls or baffles are integral with the back wall 10 of the body and project out flush with the outer face of the side wall 21 and the under side of the cover 11 is flat and when secured in place is adapted to contact with the outer edges of all of these baffles and prevent liquids or gases passing directly from the inlet to the outlet and causing them to flow in sequence through all of the zigzag passages. Furthermore, I make these walls or baffles integral with the back wall of the device so that the heat will be most efficiently transmitted to them from the exhaust manifold through the nozzle 6 and the back wall 10.

It will be obvious that other means can be provided for mounting the device on the exhaust manifold which will result in sufficient heat being transmitted to the body but I have found the method of mounting illustrated as accomplishing the result desired with a minimum expenditure of labor in making the connection.

The inlet pipe 16 may be left open or it may be connected to any suitable liquid feed means for supplying liquid such as water or hydrocarbons to the device. Preferably I connect the outlet pipe 13 to the inlet end 4 of the inlet manifold by means of a suitable pipe connection 35 and a coupling 36.

It will now be understood that as the fluids enter the device through the pipe 16 any fluid in liquid form is retained in the pockets until it is vaporized and can pass over the several vertically arranged baffles and that as the flow of gases and vaporized liquid continue through the device and pass the several horizontal baffles, the gases and vapors are highly heated before they escape through the outlet pipe 13 and it will also be readily understood that unless the device is flooded with liquid to more than its vaporizing capacity, no fluid in liquid form can reach the outlet pipe 13 or in other words, the manifold of the engine.

As many modifications of my invention will readily suggest themselves to one skilled in the art, I do not limit or confine my invention to the specific details of construction herein shown and described.

I claim:

1. A vaporizer for use in conjunction with an internal combustion engine, comprising a closed metallic casing adapted to be mounted on a portion of the engine to be heated thereby, the casing having an inlet for fluids at its upper part and an outlet at its lower part, the outlet adapted to be connected to the intake manifold of the engine, baffle walls arranged in the upper part of the casing adapted to form a plurality of liquid traps in series, and baffle walls in the lower part of the casing forming an elongated passage without traps through which gases

passing through the device must flow to reach the outlet, as and for the purpose specified.

2. A vaporizer adapted to be mounted upon the exhaust manifold of an internal combustion engine to be heated thereby, comprising a closed metallic casing having an inlet for fluids at its upper part and through which the contents are adapted to be drawn by lower than atmospheric pressure, and an outlet for gases at its lowest part, a horizontal baffle wall dividing the upper part from the lower part except at an end thereof opposite to said inlet, a series of integral partitions extending upwardly from said horizontal wall and a series of integral partitions depending from the outer wall of the casing and extending between said upwardly projecting partitions, whereby a series of independent pockets is provided which the fluid passing through the device must enter in succession, and horizontally extending superheating walls arranged between said horizontal wall and the outlet as and for the purpose specified.

3. A vaporizer for connection to the intake manifold of an internal combustion engine for supplying gases thereto and comprising a closed metallic casing adapted to be mounted on the exhaust manifold of the engine to be heated thereby, an outlet at the lower side of the casing adapted to be connected to the engine inlet between a carburetor and the cylinders, the casing having an inlet for fluids arranged above its outlet, and said casing provided with traps adapted to catch any liquid entering the casing through the inlet and retain same until it is vaporized and a plurality of superheating baffles arranged in the path of the gases between the traps and the outlet.

4. A vaporizer for connection to the intake manifold of an internal combustion engine for supplying gases thereto and comprising a closed metallic casing adapted to be mounted on the exhaust manifold of the engine to be heated thereby, an outlet at the lower side of the casing adapted to be connected to the engine inlet between a carburetor and the cylinders, the casing having an inlet for fluids arranged above its outlet, said casing provided with a series of traps through which the gases must pass successively and adapted to catch any liquid entering the casing through the inlet and retain same until it is vaporized, and superheating walls arranged in the casing between said traps and the outlet, as and for the purpose specified.

5. A vaporizer for connection to the intake manifold of an internal combustion engine for supplying gases thereto and comprising a closed metallic casing adapted to be mounted on the exhaust manifold of the engine to be heated thereby, an outlet at the

lower side of the casing adapted to be connected to the engine inlet between a carburetor and the cylinders, the casing having an inlet for fluids arranged above its outlet, said casing provided with a series of traps adapted to catch any liquid entering the casing through the inlet and retain same until it is vaporized, and superheating walls arranged in the casing between the traps and the outlet and forming an elongated zigzag passage of greater area than the outlet of the casing, as and for the purpose specified.

6. A vaporizer for connection to the intake manifold of an internal combustion engine for supplying gases thereto and comprising a closed metallic casing adapted to be mounted on the exhaust manifold of the engine to be heated thereby, an outlet at the lower side of the casing adapted to be connected to the engine inlet between a carburetor and the cylinders, the casing having an inlet for fluids arranged above its outlet, said casing provided with a succession of pockets adapted to successively catch any liquid entering the casing through the inlet and retain same until it is vaporized, and a series of horizontal superheating baffle walls arranged in the lower part of the casing between the pockets and the outlet forming a horizontal zigzag passage through which the gases must pass to reach the outlet of the casing.

7. In a device of the kind described, a closed metallic casing adapted to be mounted on the exhaust manifold of an internal combustion engine to be heated thereby, an inlet for the casing through which gases and liquids can be supplied, an outlet for the casing, a liquid trap within the casing arranged between the inlet and the outlet and adapted to trap liquid entering through the inlet and retain same until it is vaporized and means for superheating the gases after they pass the trap.

8. In a device of the kind described, a closed metallic casing adapted to be mounted on the exhaust manifold of an internal combustion engine to be heated thereby, an inlet for the casing through which gases and liquids can be supplied, an outlet for the casing, a pocket within the casing arranged between the inlet and the outlet and adapted to trap liquid entering through the inlet and retain same until it is vaporized, and superheating walls within the casing between said pocket and the outlet for highly heating gases passing through said device.

9. A vaporizer of the kind specified comprising a casing having an inlet port and an outlet port for liquid and gases, partition walls in said casing providing a continuous zig-zag passage connecting said ports, said walls arranged to provide a series of successive pockets between the ends of said pas-

sage and adjacent the inlet port for catching and retaining liquid entering the casing through the inlet port until the same is vaporized, the said passage including a delivery end portion wherein the vapors are adapted to be superheated before reaching the outlet port.

10. A vaporizer for connection to the intake manifold of an internal combustion engine for supplying gases thereto and comprising a closed metallic casing adapted to be mounted on the exhaust manifold of the engine to be heated thereby, an inlet and an outlet for the casing, said casing provided with a series of pockets adapted to successively catch any liquid entering the casing through the inlet and retain same until it is vaporized, and superheating walls

arranged in the casing between said pockets and the outlet, as and for the purpose 20 specified.

11. In a device of the kind described, a closed casing having an inlet and an outlet, the outlet adapted to be connected to the intake of an internal combustion engine for 25 drawing gases through the device, means arranged between the inlet and the outlet for trapping and holding entering liquid until vaporized, and an elongated passage between the trap means and the outlet, the 30 walls of which serve to retain any unvaporized fluid carried by the passing gases and to superheat said gases.

Signed at Chicago, Illinois, this 4th day of April, 1922.

IRVING COWLES.
